INTERNAL FIRED GAS BURNER WITH
RADIANT END WALLAlfons A. Fureczyk, Philadelphia, Pa., assignor to
Selas Corporation of America, Philadelphia,
Pa., a corporation of Pennsylvania

Application July 31, 1946, Serial No. 687,263

6 Claims. (Cl. 158—99)

1

My invention relates to burners, and more particularly to burners of the type having a substantially closed combustion space in which practically complete combustion of a combustible gaseous mixture is accomplished and from which heated products of combustion are discharged at a relatively high velocity through a restricted outlet in the form of a high temperature gas stream.

It is an object of the invention to provide an improvement in burners of this type, particularly to obtain better use of the high temperature heating gases produced by the burner. I accomplish this by providing a hollow refractory body forming the combustion space whose restricted outlet end is formed in such a manner that work during its movement past such outlet end at close range thereto is first heated primarily by radiant heat from a refractory wall heated to incandescence by the high temperature gases and while the work is out of physical contact with the primary high velocity gas stream; and the work thereafter is immediately heated to a higher temperature by moving directly into the primary high velocity gas stream.

The refractory wall past which the work initially moves and the restricted outlet through which the primary high temperature gas stream issues, are preferably embodied in a single refractory shape or insert fixed to the outlet end of the hollow refractory body. Such refractory shape is relatively small compared to the size of the hollow refractory body and may be considered in effect as a tip for the burner. The tip is of such shape that heat is concentrated at the region thereof adjacent to the refractory surface past which the work is adapted to move, so that such surface is heated to a high incandescent temperature to promote efficient initial heating of the work by radiant heat.

The above and other objects and advantages of the invention will be more fully understood upon reference to the following description and accompanying drawing forming a part of this specification, and of which Fig. 1 is a vertical sectional view, taken at line 1—1 of Fig. 2, of a burner embodying the invention; Fig. 2 is an end view looking toward the restricted outlet or tip of the burner illustrated in Fig. 1; Fig. 3 is a fragmentary vertical sectional view, taken at a right angle to Fig. 1, to illustrate the tip or restricted outlet end of the burner more clearly; Fig. 4 is an end view of a modified form of tip for the burner illustrated in Fig. 1; and Fig. 5 is a vertical sectional view of the tip shown in Fig. 4.

2

Referring to Figs. 1 and 2 of the drawing, the gas burner embodying the invention includes a ring-shaped base member 11 formed to provide an inlet chamber 12 having a threaded opening 14 which is adapted to be connected to a suitable source of supply of a combustible gaseous mixture. The base member 11 is formed with an inwardly extending shoulder 15 at the top part of the inlet chamber 12 to receive the lower flanged end 16 of a circular burner screen 17 having a plurality of small apertures 18 extending therethrough.

At the top face of the base member 11 is secured a ring-shaped clamping plate 19, as by screws 20, for example, the inner edge of which overlies the flanged end 16 of the burner screen 17. In order to obtain a gas-tight seal about the burner screen 17, a gasket 21 of suitable material, such as asbestos, for example, is interposed between the plate 19 and base member 11.

The large open end of a cup-shaped metal shell or outer casing 22 is removably secured at 23 to the base member 11. Within the metal shell 22 is provided a hollow refractory body 25 having a cavity forming a combustion space 24 terminating at its upper end in a slotted discharge orifice or restricted outlet 25.

In the burner 10 illustrated the hollow body 26 comprises a number of parts or members of high temperature refractory material including a hollow body or annular member 26 which snugly fits about the upper reduced portion of the burner screen 17 and extends above the top surface of the latter to form a short passage 27 at the inlet end of the combustion space 24.

About the hollow body 26 is disposed the lower end of a hollow cylindrical member 28 which bears against the clamping plate 19 and extends upwardly therefrom alongside of the metal shell 22 to the sloping or tapered upper end of the shell. Within the member 28 and forming therewith a part of the refractory wall of the space 24 is disposed a hollow cylindrical member 29. The lower end of the member 29 bears against the top surface of the hollow member 26, and the upper end thereof bears against the larger end of an annular member 30 which forms the discharge or outlet end of the combustion space 24. The annular member 30, which projects through the small open end of the outer shell 22, bears against the sloping or tapered part of the shell and at the extreme upper end is fixed an insert or tip 31, as will be described more fully herein-after, having an elongated narrow slot forming the restricted outlet 25 for the combustion space 24.

In order to withstand the high temperatures produced in the combustion space 24 during operation of the burner, the hollow member 26, inner cylindrical member 28 and upper annular member 30 may be formed of a suitable refractory material, such as silicon carbide, for example, having high resistance to thermal shock and possessing rigidity and strength at high temperatures. The outer cylindrical member 28 is preferably formed of a refractory material, such as mullite, for example, possessing good insulating properties and having adequate strength to serve as the outer portion of the refractory wall. Although not to be limited thereto, the burner screen 17 may be formed of a refractory material, such as aluminum oxide, for example.

The refractory wall parts just described may be secured to one another and within the outer shell 22 by a suitable high temperature air-hardening cement, as indicated at 32, 33, 34 and 35, respectively. Such a high temperature cement upon hardening provides a rigid and unitary burner structure in which all of the refractory wall parts are effectively united to form the combustion space 24.

To operate the burner 10 to produce a high velocity gas stream of heated products of combustion, a combustible fuel mixture comprising a gaseous fuel and a combustion supporting gas is supplied through the inlet 14 from a suitable source of supply. When the burner 10 is relatively cool and at a low temperature, the gaseous mixture supplied thereto passes through the inlet chamber 12, burner screen 17 and space 24 from which it is discharged through the restricted outlet 25. The combustible gaseous mixture is initially supplied to the burner 10 at a relatively low pressure which may be equivalent to a pressure corresponding to about 5 or 6 inches of water column, for example, so that the gaseous mixture discharged from the space 24 can be ignited to produce and maintain a flame at the outlet 25.

When a flame is being maintained at the outlet 25, the pressure of the gaseous mixture supplied to the burner 10 may be momentarily reduced sufficiently to cause the flame to backfire through the outlet 25 onto the burner screen 17 in space 24. When this occurs a plurality of flames are produced and maintained at the upper ends of the small apertures 18.

When the flames are being maintained within the space 24 at the top surface of the burner screen 17, the pressure of the gaseous mixture supplied to the burner 10 may then be increased. After a short interval of time the flames maintained at the top surface of the burner screen 17 effect such heating of the inner refractory lining that these surfaces are heated to a high incandescent temperature. The heating of the inner refractory lining to a highly incandescent condition and radiant heat therefrom promotes substantially complete combustion of the gaseous mixture in the combustion space 24 before the mixture reaches the outlet 25. From the outlet 25 is discharged a high velocity jet or stream of heated gases at a temperature nearly equal to the temperature in the combustion space 24 and consisting substantially entirely of heated products of combustion.

During normal operation the burner 10 is characterized by the absence of a bright and luminous flame. It is only when the burner is first started that a flame is momentarily maintained at the elongated slot or outlet 25, as previously explained. After the gaseous mixture has once

5

been ignited, the delivery pressure of the mixture is reduced sufficiently to cause backfiring into the combustion space 24, so that burning of the gaseous mixture will be initiated at the top surface of the burner screen 17.

In a burner of the type just described, the heated products of combustion are discharged from the combustion space 24 through the restricted outlet 25 at an elevated temperature ranging from 2700° F. to 2900° F. and higher when a combustible gaseous mixture of air and ordinary gas, such as city gas having a b. t. u. rating of about 550 b. t. u. per cubic foot, for example, is supplied at a pressure in the neighborhood of three pounds per square inch. Under such operating conditions the pressure in the combustion space 24 may be equivalent to a pressure corresponding from 55 to 70 inches of water column and appreciably above that of atmospheric pressure. The heated gases are discharged from the burner at an average velocity of about 750 feet or more per second and at a maximum velocity of about 1000 feet or more per second.

In many heating applications it has been the practice to employ burners of the type herein described to effect heating of work entirely by the high temperature gas stream into which the work is adapted to pass at a region closely adjacent to the restricted outlet. In other words, the work is heated from the ambient temperature to the desired elevated temperature entirely by the high temperature gas stream.

In certain heating applications, heating of the work entirely by the gas stream does not utilize the high temperature gases efficiently. This is particularly true when work of elongated extent is moved into the gas stream at a region closely adjacent to the restricted outlet. This is so because the portion of the gas stream, through which successive longitudinal portions of elongated work initially pass, is only utilized to heat the work to an intermediate temperature short of the final temperature to which the work is ultimately heated by the portion of the gas stream into which the work subsequently passes. Stated another way, all parts of the gas stream are at a high temperature capable of heating successive longitudinal portions of the work to the desired elevated temperature, but only the part of the gas stream into which the work passes after being initially heated is effectively utilized in this manner.

In accordance with the invention, in order to obtain better use of the high temperature products of combustion formed in the combustion space 24, these heated gases are utilized to heat to incandescence a refractory wall 36 which is adjacent to the restricted outlet 25 and over which the work is adapted to move before passing into the gas stream issuing from the restricted outlet. The work passing over the refractory wall 36 at close range thereto is effectively preheated by radiant heat therefrom to bring successive portions of the work to an intermediate temperature short of the final high temperature to which the work is ultimately heated. By preheating work in this manner, successive portions of the work are heated to the desired final elevated temperature in the gas stream in a shorter interval of time while being impinged by the high temperature heated products of combustion.

To heat the refractory wall 36 to as high an incandescent temperature as possible and effect optimum radiant heating of work before passing

into the gas stream, the exterior surface thereof is formed with a multiplicity of recesses 37. A small portion of the heated products of combustion generated and developed in the combustion space 24 is diverted from the restricted outlet 25 and pass through tiny passages 38 in the refractory wall 36 which communicate with the inner ends or bottoms of the recesses 37 which are of cylindrical form and more or less U-shaped in section, as shown in Figs. 1 and 3.

By providing the recesses 37 which are considerably larger in cross-sectional area than the passages 38, the heated gases emerging from the passages into the recesses immediately expand laterally, whereby the velocity of the gases passing from the open ends of the recesses is slowed down considerably. The passages 38 are quite small and only divert a sufficient quantity of heated products of combustion to insure heating the inner wall surfaces of the recesses 37 to a high incandescent temperature.

By heating the inner wall surfaces of the recesses 37 to incandescence in the manner just described, efficient radiant heating of work is effected when the work passes over the recesses at close range to the refractory wall 36, in the manner indicated at 39 in Fig. 5. After the work is preheated by radiant heat from the refractory wall 36, successive longitudinal portions of the work pass directly into the primary gas stream issuing from the restricted outlet 25 to heat the work to the desired final high temperature.

In certain instances the final elevated temperature to which the work is heated may be the fusing temperature of the work, as when a glass filament or rod is fed into the high temperature gas stream, for example. In heating applications of this kind, the interval of time in which successive longitudinal portions of the work must be impinged by the heated products of combustion, to bring the work to a fusing temperature, is materially shortened by preheating the work with the aid of the refractory wall 36 at the outlet end of the hollow refractory body.

It will now be understood that the work moving toward the primary gas stream produced at the restricted outlet 25 is first heated primarily by radiant heat from the refractory wall 36 while the work is out of physical contact with the primary gas stream. While the heated products of combustion discharged from the recesses 37 envelop the work adjacent to the refractory wall 36, such gases are slow moving gases and are not relied upon to effect rapid convection heating of the work in the same manner as the high velocity primary gas stream. Moreover, only a relatively small quantity of heated products of combustion is diverted through the tiny passages 38 which is just sufficient to maintain the inner wall surfaces of the recesses 37 in a highly incandescent condition.

Since the heated products of combustion in the combustion space 24 are constantly sweeping over the inner face of the refractory wall 36, such heated gases contribute to heating the entire mass of the wall 36 to an incandescent temperature. Therefore, heat is effectively conducted through the wall 36 to the entire surface area at the outer face of the wall 36 due to the continuous heating of the inner face thereof by the heated products of combustion sweeping over the wall. In addition, such heating of the inner face of the wall 36 reduces the heat loss from the inner wall surfaces of the recesses 37, so that the latter will be maintained at a high incandescent temperature.

In Figs. 4 and 5 I have shown a modified form of burner tip in which recesses 37a are formed at the inner face rather than at the outer face of a refractory wall 36a. In such modified form of burner tip, no passages for diverting products of combustion extend from the bottoms of the recesses 37a to the outer face of the refractory wall 36a. However, by providing the multiplicity of recesses 37a at the inner face of the refractory wall 36a which are of such depth that a relatively thin wall section 40 is formed between the bottoms of the recesses and the outer face of the refractory wall 36a, such thin wall section can be readily heated to a high incandescent temperature. This is so because the high temperature heated products of combustion in the combustion space 24 are diverted into the pockets or cups formed by the recesses 37a to heat the inner wall surfaces thereof to incandescence.

Since the overall inner wall surface area presented to the heated products of combustion is considerably greater than the exposed surface area at the outer face of the refractory wall 36a, heat is effectively conducted through the refractory wall from its inner face to the outer face. Moreover, by forming the refractory wall 36a so that the thicknesses of the walls between adjacent recesses are relatively small, heat is rapidly conducted through the mass of the refractory wall to the thin wall section 40 at which region heat is concentrated to maintain the outer face of the tip at an extremely high incandescent temperature to promote radiant heating of work.

In the embodiment first described and also in the modified form of Figs. 4 and 5, the refractory wall is at the extreme outer end of the hollow refractory body and contiguous to and directly at one side of the elongated restricted outlet 25, whereby the highest temperature heated products of combustion about to issue from the combustion space 24 are effectively utilized to heat the refractory walls 36 and 36a to incandescence and then immediately pass through the restricted outlet 25 in a path of flow characterized by the absence of any barriers or flow impediment walls tending to reduce the velocity at which the heated gases discharge from the burner tip. In this way newly formed heated products of combustion are continuously flowing freely and sweeping over the inner faces of the refractory walls 36 and 36a, before entering the restricted outlet 25, to maintain the outer faces thereof at a high incandescent temperature.

In order to facilitate the fabrication of burners of the kind described and embodying the invention, the refractory walls 36 and 36a and restricted outlets 25 adjacent thereto are embodied in relatively small refractory shapes which are U-shaped in section and may be referred to as tips or inserts for the burners. As best shown in Figs. 2 and 4, the independent tip units 31 and 31a are octagonal-shaped and the longer side walls thereof formed with outwardly extending shoulders 41. The annular member 39 of the hollow refractory body is formed with recesses 42 to receive the shoulders 41 and the tips 31 and 31a may be securely fixed in position in the annular member 39 in any suitable manner, as by a suitable high temperature air-hardening cement, for example. This produces an inexpensive and easily manufactured construction and provides a burner tip of the type described and illustrated which possesses exceptional strength.

It is desirable to form a burner tip like the independent tip units 31 and 31a of a refractory

material, such as beryllium oxide, for example, because such material can withstand exceptionally high temperatures and possesses good heat conductive properties. Since refractory materials like beryllium oxide are relatively expensive, it is desirable to reduce the quantity of such material employed to provide the hollow refractory body. This is made possible by providing the tips 31 and 31a which are relatively small and inserting such tips into the larger annular member 30 which may be formed of less expensive refractory material, such as silicon carbide, for example.

Although I have illustrated and described particular embodiments of my invention, I do not desire to be limited to the particular arrangements set forth, and I intend in the following claims to cover all modifications which do not depart from the spirit and scope of the invention.

What is claimed is:

1. A gas burner for heating work comprising structure including a hollow body which provides a substantially closed combustion space having an inlet through which fuel to be burned in said space is introduced and a restricted outlet through which products of combustion are exhausted, said space having its inner wall surface and outlet composed substantially entirely of high temperature refractory material, the end of said body adjoining said restricted outlet including a thin refractory wall forming on its outer portion an exposed surface, said wall at a face thereof having a plurality of spaced apart recesses, said recesses being formed at the outer face of said wall, and tiny passages formed in the latter for diverting products of combustion from said space into said recesses.

2. A gas burner for heating work comprising structure including a hollow body which provides a substantially closed combustion space having an inlet through which fuel to be burned in said space is introduced and a restricted outlet through which products of combustion are exhausted, said space having its inner wall surface and outlet composed substantially entirely of high temperature refractory material, the end of said body adjoining said restricted outlet including a thin refractory wall forming on its outer portion an exposed surface, said wall at a face thereof having a plurality of spaced apart recesses, said recesses being formed with substantially straight walls normal to and extending inwardly from the outer face of said refractory wall, and tiny passages formed in said wall for diverting products of combustion from said space into said recesses,

5

said passage being considerably smaller in cross-section than said recesses to promote lateral expansion of the products of combustion entering said recesses.

3. A gas burner for heating work comprising structure forming a combustion chamber having an inlet through which fuel is introduced to be burned in the chamber and having restricted outlet through which the products of combustion are exhausted, an insert to be placed in said restricted outlet being made of material having high heat conductivity, said insert being substantially cup-shaped and having an opening in the bottom adjacent to one side thereof through which the products of combustion pass, the remainder of the bottom being of substantially uniform thickness.

4. A gas burner for heating work comprising structure forming a combustion chamber having an inlet for fuel and a restricted outlet through which products of combustion are exhausted, a refractory tip member made of material having a high heat conductivity located in said outlet, said tip being provided with an elongated opening adjacent to one edge thereof and having on its exterior a flat surface extending from said opening toward the other edge thereof, said member being of substantially uniform thickness throughout the area thereof covered by said surface.

5. The combination of claim 4 in which the surface of said tip is provided with a plurality of recesses extending from its exterior face toward the interior thereof.

6. The combination of claim 4 in which said tip is provided with a plurality of recesses extending from the interior thereof toward the outer surface.
